US0D1103608S

(12) **United States Design Patent** (10) **Patent No.:** **US D1,103,608 S**
(45) **Date of Patent:** **** Dec. 2, 2025**

(54) **HEEL COMPONENT**

(71) Applicant: **SHENZHEN STARLINK
NETWORK TECHNOLOGY CO.,
LTD, Shenzhen (CN)**

(72) Inventors: **Jie Huang, Shenzhen (CN); Yufeng
Tsai, Shenzhen (CN)**

(73) Assignee: **SHENZHEN STARLINK
NETWORK TECHNOLOGY CO.,
LTD, Shenzhen (CN)**

(**) Term: **15 Years**

(21) Appl. No.: **29/945,489**

(22) Filed: **Jun. 4, 2024**

(30) **Foreign Application Priority Data**

Dec. 25, 2023 (CN) 202330851296.8

(57) **CLAIM**

The ornamental design for a heel component, as shown and described.

DESCRIPTION

FIG. 1 is a top front perspective view of a heel component showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view thereof taken along line 9-9 in FIG. 3; and,

FIG. 10 is a top front perspective view of the heel component, shown in use with the heel component in a shoe.

The broken lines show the shoe environment and form no part of the claimed design. The cross-section is provided to clarify the design.

1 Claim, 10 Drawing Sheets
